[57] CLAIM

The ornamental design for a roofing material cutter, as shown.

DESCRIPTION

FIG. 1 is an elevational view of one side of a roofing material cutter, showing our new design;
FIG. 2 is an elevational view of the opposite side thereof;

FIG. 3 is a top plan view thereof;

FIG. 4 is a bottom plan view thereof;

FIG. 5 is an elevational view of the left-hand end of the design as shown in FIG. 1; and,

FIG. 6 is an elevational view of the right-hand end of the design as shown in FIG. 1.
